J. R. TAYLOR

GAS BURNER

Filed May 31, 1922

UNITED STATES PATENT OFFICE.

JOHN R. TAYLOR, OF MANSFIELD, OHIO, ASSIGNOR TO THE HARTMAN-SPRENG COMPANY, OF MANSFIELD, OHIO, A CORPORATION OF OHIO.

GAS BURNER.

Application filed May 31, 1922. Serial No. 564,993.

To all whom it may concern:

Be it known that I, JOHN R. TAYLOR, a citizen of the United States, residing at Mansfield, in the county of Richland and

5 State of Ohio, have invented certain new and useful Improvements in Gas Burners, of which the following is a specification.

My invention relates to improvements in gas burners, the present embodiment of the 10 invention being particularly designed and adapted for use in connection with gas heaters of the radiator or mantle type.

The primary object of the invention is to provide a generally improved gas burner 15 of the type or class indicated which will be exceedingly simple in construction, cheap of manufacture and efficient in use.

A further and very important object is the provision of an improved burner of the 20 manifold type having its parts and features so arranged and disposed relative to each other as to provide a fluid supply chamber in which the combustible fluid is distributed and equalized as to pressure to the burner 25 openings or gas jet nozzles throughout the entire length of the elongated burner or bar whereby an equal distribution of gas is obtained to the burner openings or ports and consequently resulting in gas jets or flames 30 of equal length resulting in a perfecting and augmenting of combustion and increased heating efficiency of the gas burner or radiator as a whole.

A still further and important object is the 35 provision of an improved elongated or manifold gas burner of this type having an improved arrangement or grouping of burner openings or nozzles and radiator supporting abutments adapted to support the 40 lower edges of the hollow radiator elements or mantles and afford suitable secondary passages for affording more perfect combustion and directing the jets or flames to the interior portions of the respective radiator elements so that the latter will continuously absorb and radiate heat which 45 would otherwise be lost.

A still further object is the provision of a 50 manifold gas burner of elongated form provided with a central fluid inlet of gradually tapering form or area toward the ends of the burner together with an improved baffle plate above the fluid inlet adapted to divert the combustible fluid outwardly into

the tapered portions of the fluid chamber 55 and thereby equalize the pressure and distribution of the combustible fluid to the various burner openings or nozzles.

With the above mentioned and other ends in view, the invention consists in the novel 60 construction, arrangement and combination of parts, hereinafter described, illustrated in one of its embodiments in the accompanying drawings, and particularly pointed out in the appended claims. 65

Referring to the drawings, forming a part of this specification, Figure 1 is a front elevation of a burner constructed in accordance with this invention applied to a gas heater of the radiator or mantle type, 70 the central or gas inlet and baffle portion thereof being broken away for the purpose of clearer illustration of the parts.

Fig. 2, an enlarged central transverse cross sectional view of the same. 75

Fig. 3, a fragmentary top plan view of the burner, the radiator and back brick elements being removed for the purpose of clearer illustration of the arrangement or grouping of the burner nozzles and radiator 80 and back brick supporting elements.

Similar numerals of reference designate like parts throughout all the figures of the drawings.

The improved burner comprises a relatively flat elongated burner member or bar 1, and a subjacent elongated manifold 1^a, having outwardly diverging or tapering walls 1^b, the walls of the burner bar 1, proper, and of the manifold 1^a and 1^b conjointly forming a fluid supply chamber 1^c. The manifold is provided on its underside with a fluid inlet 1^d, communicating with a suitable fluid supply pipe 1^e. As the terminal portion of the pipe 1^e extends horizontally or in the general direction of the length of the manifold the inlet portion 1^d is preferably placed somewhat beyond the longitudinal center of the burner and manifold so as to compensate somewhat for the initial flow and pressure of the gas in the opposite end of the manifold as the gas flows through the fluid inlet pipe and as illustrated very clearly in Fig. 1 of the drawings. 100

By reason of the tapering of the walls 1^b of the manifold it will be seen that the chamber 1^c has its largest cross sectional area through the inlet portion thereof and

that the same is of gradually decreasing cross sectional area toward the ends of the burner bar and manifold.

The ends of the burner are provided with brackets 1^f, adapted to be secured to the side or end walls 2, of the heater body or casing of a heater of the type mentioned.

- 10 The burner bar or member 1 is provided upon its top side with suitably arranged and grouped nozzles 1^g, adapted to enter the lower open ends of the hollow radiator sections or mantle elements 3, said nozzles 1^g being surrounded by supporting abutments or flanges 1^h, to receive and support the lower 15 edges of the radiator elements 3 and afford suitable secondary air passages to the respective groups of burner nozzles leading to the interior portions of the respective radiator elements. The burner may also be provided 20 with rearwardly extending brackets 1ⁱ, to receive and support the back brick or radiator wall 4.

As a means of intercepting and diverting the combustible fluid or gas as the same 25 enters through the fluid supply pipe 1^e and fluid inlet 1^d, the front and rear walls of the manifold are provided with a baffle plate 1^j, which provides subjacent branch passages 1^k, adapted to communicate with the respective tapered portions of the manifold and evenly distribute the combustible fluid along the burner bar 1 and equalize the pressure to the nozzles or burner openings 1^g. The baffle 1^j is preferably provided with a central 30 perforation 1^l, immediately above the inlet portion 1^d of the manifold.

Having thus described one of the embodiments of my invention, without having attempted to set forth all the forms in which 40 it may be made, or all the modes of its use, what I claim and desire to secure by Letters Patent is,—

45 1. A gas burner and manifold including outwardly tapering end portions and an intermediate portion of relatively large cross sectional area having a fluid inlet spaced nearer one tapered end portion than the other, and a fluid feed pipe extending along and approximately parallel with the further

spaced tapered end portion to compensate 50 for the initial flow of the combustible fluid into the opposite or shorter tapered portion of said manifold.

2. A manifold gas burner of elongated and tapered form provided with a fluid inlet 55 pipe and forming a fluid chamber tapering from said inlet pipe to the ends of said burner, and a centrally perforated horizontal baffle in said chamber above said fluid inlet pipe adapted to intercept and divert 60 the fluid from said inlet pipe outwardly into the tapering portions of said fluid chamber.

3. A gas burner, including a burner bar having burner nozzles, said burner bar being provided with a subjacent manifold having a fluid inlet intermediate the ends of said burner bar, said manifold converging outwardly gradually and progressively toward the ends of said burner bar, said burner bar and subjacent manifold conjointly forming a fluid supply chamber having its largest cross sectional area above said inlet and gradually tapering portions extending to the ends of said burner bar, and a horizontal baffle in said manifold above said inlet and extending parallel with said burner bar to distribute the fluid along said burner bar and equalize the pressure to said nozzles. 70 75

4. A gas burner, including a horizontal 80 burner bar having upwardly extending burner nozzles, said burner bar being provided with a subjacent manifold having a fluid inlet between the ends of said burner bar and manifold and converging outwardly 85 gradually and progressively toward the ends thereof, said burner bar and manifold conjointly forming a fluid supply chamber having its largest area above said fluid inlet and having a gradually tapering area toward the ends of said burner bar and manifold, and a centrally perforated baffle in said manifold above said inlet to distribute the combustible fluid along said burner bar and equalize the pressure to said nozzles. 90 95

In testimony whereof I have affixed my signature.

JOHN R. TAYLOR.
